UNITED STATES PATENT OFFICE.

SAMUEL J. GINSBURG, OF DENVER, COLORADO.

PHONOGRAPH ATTACHMENT.

1,418,251.

Specification of Letters Patent. Patented May 30, 1922.

Application filed May 3, 1921. Serial No. 436,552.

To all whom it may concern:

Be it known that I, SAMUEL J. GINSBURG, a citizen of the United States, residing at Denver, in the county of Denver and State 5 of Colorado, have invented certain new and useful Improvements in Phonograph Attachments; and I do hereby declare the following to be a full, clear, and exact description of the invention, such as will enable 10 others skilled in the art to which it appertains to make and use the same.

This invention relates to new and useful improvements in phonograph attachments and has for its primary object the provision 15 of means for visibly indicating the exact tension of the propelling spring of the phonograph motor, whereby a person may readily determine approximately the number of records played since the winding of the 20 spring and the number of records which may be still played before the exhaustion of the spring.

Another object of this invention is the provision of an automatic alarm adapted to 25 warn the operator of the approximate exhaustion of the spring and also warn the operator when the spring has become fully wound, to prevent over-winding and thereby obviate the danger of injuring or breaking 30 the spring and other parts associated therewith.

A further object of this invention is the provision of a phonograph attachment of the above stated character which will be simple, 35 durable, and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

45 For a complete understanding of my invention, reference is to be had to the following description and accompanying drawings, in which:—

Figure 1 is a fragmentary vertical sectional view illustrating a portion of a phonograph with my invention applied thereto,

Figure 2 is a fragmentary horizontal sectional view taken on the line 2—2 of Figure 1,

55 Figure 3 is a plan view illustrating the indicator and the scale plate,

Figure 4 is a sectional view taken on the line 4—4 of Figure 1,

Figure 5 is a detail view illustrating a guide for the indicating rod, 60

Figure 6 is a detail sectional view illustrating a connecting rod between the spring of the motor and the feed nut.

Referring in detail to the drawings, the numeral 1 indicates a fragmentary portion 65 of a phonograph cabinet having located therein a spring motor 2 of a conventional type for driving the record table 3. The spring 4 of the spring motor 2 is wound by a shaft 5 by having its inner end secured to 70 said shaft while the outer end is secured to the casing 6 which rotates during the unwinding of the spring. The shaft 5 is rotated by a crank 7 for the purpose of winding the spring 4. The foregoing description 75 relates to a well known construction of phonograph and to which my invention is applied.

The shaft 5 is extended and has formed thereon screw threads 8 which cooperate 80 with screw threads in a feed nut 9 mounted on the extended end of the shaft 5. The feed nut 9 has pivotally secured thereto a connecting arm 10 constructed of telescopic sections and has its other end pivotally connected to the outer convolution of the spring 4 and adjacent to the end of the spring which is attached to the casing 6 of the 85 spring motor 2. The feed nut 9 has formed thereon a grooved collar 11 engaged by the 90 forked end 12 of an indicating rod 13. The indicating rod 13 is slidably mounted in a series of horizontally disposed guides 14 carried by the cabinet 1 and the upper end of said rod projects through a slot 15 in the 95 top wall of said cabinet and also through a slot 16 formed in an indicating or scale plate 17. The plate 17 is secured to the top wall of the cabinet 1 adjacent to the table 3 and in clear view of the operator. The upper end of the rod 13 has formed thereon an indicator 18 adapted to travel over the scale 100 upon the plate 17 on the movement of the rod 13 so that the operator may readily determine at a glance just the condition of the 105 spring 4.

In operation, the spring 4 of the spring motor 2 is wound by the rotation of the shaft 5 in one direction and during the unwinding of the spring 4 to operate the turn 110 table 3 the casing 6 rotates in the same direction as the rotation of the shaft 5 to wind

the spring, consequently the rotation of the shaft 5 to wind the spring causes the feed nut 9 to move in one direction carrying with the same the indicating rod which causes 5 the indicator 18 to move in one direction on the scale plate 17. The unwinding of the spring 4 to propel or rotate the table 3 as before stated, the casing 6 rotates in the same direction as the shaft 5 and owing to 10 the fact that the arm 10 is connected to the outer convolution of the spring 4 the feed nut 9 is rotated on the screw threads 8 of the shaft 5 and caused to move in a direction opposite to the first described direction, thus moving the indicator 18 in an 15 opposite direction over the scale plate 17.

An alarm 19 of any well known construction is located within the cabinet 1 and is provided with a pair of actuating arms 20 and 21. The actuating arms are so disposed 20 that the movement of the indicating rod 13 is between said arms so that upon the indicating rod reaching approximately the end 25 of its movement in either direction engages one of the arms and actuates the alarm 19 thus indicating to the operator the approximate exhaustion of the spring and also warns the operator when the spring has become fully wound to prevent overwinding.

30 While I have shown and described the preferred embodiment of my invention, it will be understood that minor changes in construction, combination, and arrangement 35 of parts may be made without departing from the spirit and scope of the invention as claimed.

Having thus described my invention what I claim is:—

1. In combination, a spring motor having 40 a spring secured to a rotatable shaft and a casing, a feed nut moved in one direction by the rotation of the shaft, means connecting the feed nut to the outer convolution of the spring to cause the feed nut to rotate with 45 the casing on the unwinding of the spring to cause movement of the feed nut in an opposite direction, and an indicator operated by the movement of the feed nut.
2. In combination, a spring motor includ-

ing a spring connected to a rotatable shaft 50 and a rotatable casing, feed threads formed on said shaft, a feed nut on said feed threads, and caused to move in one direction by the rotation of said shaft, means connecting the feed nut to the outer convolution 55 of the spring adjacent to its attachment to the casing to cause said feed nut to rotate with the casing and cause movement of the feed nut in an opposite direction, and an indicator connected to the feed nut and 60 adapted to move with the same.

3. In combination, a spring motor including a spring connected to a rotatable shaft and a rotatable casing, feed threads on said shaft, a feed nut on said feed threads, an 65 indicator connected to said feed nut, and an adjustable arm pivoted to the feed nut and to the outer convolution of the spring.

4. In combination, a phonograph including a cabinet and a spring motor having a 70 spring connected to a rotatable shaft and a rotatable casing, feed threads on said shaft, a feed nut on said feed threads and adapted to be moved in one direction by the rotation of said shaft, an adjustable telescopic arm 75 connecting the feed nut to the outer convolution of the spring for causing said feed nut to rotate with the casing and move on the shaft in a direction opposite to the first named direction, a grooved collar formed on 80 said nut, an indicating rod having a forked end engaging the grooved flange, guides carried by the cabinet and receiving the indicating rod, an indicating plate carried by said cabinet, a pointer carried by the indicating rod and movable over the plate, an alarm located in the cabinet, and actuating arms for said alarm and adapted to be engaged by the indicating rod when the latter reaches the approximate end of its movement in either direction.

In testimony whereof I affix my signature in presence of two witnesses.

SAMUEL J. GINSBURG.
